OPERATING DEVICE FOR USE IN CONNECTION WITH COKE-OVEN DOORS

Charles Craib Middleton and Reginald Frank Krall, London, England, assignors to Woodall-Duckham (1920) Limited, London, England, a British company

Application August 17, 1936, Serial No. 96,498
In Great Britain October 4, 1935

7 Claims. (Cl. 202—270)

The present invention relates to improved operating devices for use in connection with coke-oven doors. The invention is applicable to coke-oven doors which are tightened in position against the oven mouth by the pressure exerted by screws bearing against arms which engage with latches attached to the oven battery. Conversely, these screws must be released prior to removing the door from the oven. This method of securing the door in place is generally provided on "self-sealing" doors, which usually have two such screws, one near the bottom of the door, and the other near the top; on account of the height of the door, the top screw is frequently about 12 feet above the level of the bench.

It is the conventional practice to tighten and loosen the top screw by means of a heavy long-handled spanner, which must be lifted into position by the operator standing on the bench. The objects of the present invention are to eliminate the excessive effort required to effect this operation, and, in addition, to reduce considerably the time required for tightening or loosening the top screws.

A coke-oven door has already been proposed in which the top and bottom screws of each door are interconnected by mechanism whereby both screws can be tightened simultaneously from the bench level, but this arrangement necessitates the provision of special mechanism on each door. The present invention obviates the necessity for the above, or analogous devices.

According to the present invention, we provide an arrangement for turning the top screws of coke-oven doors from bench level, in which a device, comprising a spanner-head for engaging the screw-heads suspended at about the level of the top screws and interconnected with operating means at bench level for turning the spanner-head, is movably mounted on a rail or runway extending along the oven battery, whereby the device may be moved from one door to another as required.

In the preferred form of the invention, the spanner-head is suspended by a flexible suspension, such as a chain, from a carriage movable along a rail at the top of the oven battery, and the suspension is arranged to permit a small vertical movement of the spanner-head to engage individual screws, the height of which may vary slightly from door to door. Preferably also, the spanner-head incorporates ratchet mechanism, as hereinafter described, operated through a long handle extending down to a convenient height above the bench, so that the spanner-head can

be rotated, as in known ratchet spanners, by the to-and-fro motion of the handle by the operator.

The lower screws on the doors are turned with a short spanner, from bench level, as heretofore.

The invention is more particularly described with reference to the accompanying drawings, in which:—

Figure 1 shows a front elevation of a travelling spanner, according to the present invention, in relation to a battery of coke-ovens.

Figure 2 is a side elevation, partly in section, corresponding to Figure 1.

Figures 3 and 4 show, on an enlarged scale, the details of a spanner-head, Figure 3 being a section on the line A—A of Figure 4, and Figure 4 a section on the line B—B of Figure 3; and

Figure 5 illustrates a simplified form of the spanner.

Referring to Figures 1, 2, 3, and 4, which illustrate our preferred form of the invention, Figure 1 shows part of a battery of coke-ovens, the oven doors 6 being held in position against the oven mouth by the pressure of the screws 7 and 1a bearing against arms 8 which engage with latches 9 attached to the steelwork of the oven. In accordance with the present invention, the top screw-heads 7 are now turned by the spanner-head 10, actuated as hereinafter described through the long handle which is shown depending to a suitable level above the bench 1. The spanner is suspended by a chain 2 from one end of the arm 11, the other end of which carries a counterweight 12 (see Figure 2). The arm 11 is pivoted about a horizontal axis on a carriage 13, running on a rail 14 along the top of the oven battery.

As stated above, the spanner-head is turned through ratchet mechanism, so avoiding the necessity for removing the spanner, and replacing it on the screw-head between each turn. The ratchet mechanism is shown in detail in Figures 3 and 4. The spanner-head 15 carries a ratchet portion 16, and can rotate in the support 17, which is attached to the chain 2 by a swivelling link 18. The handle of the spanner is attached to the member 19, which is also journaled in the support 17, and which carries the pawl 20. It is clear that movement of the handle from right to left on Figure 3 will operate to screw up the screw, the return stroke slipping the ratchet. When it is required to unscrew a screw, the spanner is turned through 180° on the swivelling link 18, and left to right movement of the handle will now unscrew the screw.

The ratchet mechanism referred to may be

replaced by worm gearing, which is operated from bench level by an endless chain.

It will be seen from Figure 2 that the action of pulling down the spanner to engage it with the screw-head causes the head of the spanner to move inwards towards the screws, as the arm 11 becomes more nearly horizontal. By this means, the spanner is easily brought into engagement with the screw-head, and when engaged has no tendency to slip off during the operation. As already stated, the height of the various screws may vary slightly from door to door, and the arrangement of Figure 2 permits the requisite vertical movement of the spanner-head.

Figure 5 illustrates a simplified form of the spanner which may be used in certain circumstances. A long-handled ordinary spanner is suspended by a chain and a spring 21 from a movable carriage 13, arranged as before. The spring 20 permits a small vertical movement of the spanner-head, in order to engage different screws at different levels, as in the case of the arrangement referred to in the preceding paragraph. The chain is sufficiently flexible to allow the requisite rotational movement of the head of the spanner. In this embodiment, the spanner must be removed from the screw-head and replaced thereon between each turn, but as the weight of the spanner is now taken by the suspension, the physical exertion on the part of the operator is correspondingly reduced.

Instead of suspending the spanner from a carriage on an overhead rail, it may be suspended or pivoted at the top of a small tower running on 35 wheels along the bench.

An important advantage of the present invention is that the spanner is independent of the door-operating machine, and hence the machine, after use on one door, can be moved to another 40 door while the adjustment of the screws on the first door is in progress, operating time being economized thereby.

What we claim is:—

1. In a coke oven having a door held in closed 45 position by upper and lower screws which lie in a common vertical plane parallel to the face of the door, the combination of means for releasing the upper screw comprising a support, a wrench carried by said support and suspended therefrom above the upper screw and in laterally spaced 50 relation with reference to the plane of the screws, means for connecting the wrench to the support so that it can be lowered into alignment with the top screw, said connection including means for 55 simultaneously causing the wrench to approach the plane of the screws as it is lowered, and means for operating said wrench.

2. In a coke oven having a door held in closed 60 position by upper and lower screws which lie in a common vertical plane parallel to the face of the door, the combination of means for releasing the upper screw comprising a support, a wrench carried by said support and suspended 65 above the upper screw and in laterally spaced relation with reference to the plane of the screws, means for connecting the wrench to the support so that it can be lowered into alignment with the top screw, said connection including means causing 70 the wrench to simultaneously move to a position above the top screw and away from the plane of the screws when released therefrom, and means for operating said wrench.

3. In a coke oven having a door held in closed 75 position by upper and lower screws which lie in a common vertical plane parallel to the face of the

door, the combination of means for releasing the upper screw comprising a support, a wrench carried by said support and suspended therefrom above the upper screw and in laterally spaced relation with reference to the plane of the screws, 5 means for connecting the wrench to the support, said means including a lever pivoted to the support intermediate its ends, a counterweight on one end of said lever, and a connection between the other end of the lever to the wrench, the 10 counterweight normally elevating the wrench to a position above and to one side of the top screw whereby upon lowering of the wrench into alignment with the top screw the wrench simultaneously moves toward the plane of the screws, and 15 means for operating the wrench.

4. In a byproduct coke oven having a door held in closed position by upper and lower screws which lie in a common vertical plane parallel to the face of the door, the combination of means for releasing the upper screw comprising a support, a wrench carried by said support and suspended 20 above the upper screw and in laterally spaced relation with reference to the plane of the screws, means for connecting the wrench to the support 25 so that it can be lowered into alignment with the top screw, said connection including a spring causing the wrench to simultaneously move to a position above the top screw and away from the plane of the screws when released therefrom, and 30 means for operating said wrench.

5. In a battery of coke ovens having doors held in closed position by upper and lower screws lying in a common vertical plane parallel to the faces 35 of the doors, the combination of means for releasing the upper screws comprising a support, a track carried by said support in parallel relation to the faces of the doors and spaced laterally from the plane of the screws, a carrier movable along said track, a wrench carried by said carrier 40 and suspended above the upper screws and in laterally spaced relation with reference to the plane of the screws, means for connecting the wrench to the support so that it can be lowered 45 into alignment with the top screw, said connection also including means for simultaneously causing the wrench to approach the plane of the screws as it is lowered, and means for operating said wrench.

6. In a battery of coke ovens having doors held 50 in closed position by upper and lower screws which lie in a common vertical plane parallel to the faces of the doors, the combination of means for releasing the upper screws comprising a support, a track carried by said support in parallel 55 relation to the faces of the doors, and spaced laterally from the plane of the screws, a carrier movable along said track, a wrench carried by said carrier and suspended above the upper screws and in laterally spaced relation with reference 60 to the plane of the screws, means for connecting the wrench to the support so that it can be lowered into alignment with the top screw, said connection including means causing the wrench to simultaneously move to a position above the top screw and away from the plane of the screws when released therefrom, and means for operating 65 said wrench.

7. In a coke oven having a door held in closed 70 position by upper and lower screws which lie in a common vertical plane parallel to the face of the door, the combination of means for releasing the upper screw comprising a support, a wrench carried by said support and suspended above the upper screw and in laterally spaced relation with 75

reference to the plane of the screws, means for connecting the wrench to the support so that it can be lowered into alignment with the top screw, said connection including means causing the wrench to simultaneously move to a position above the top screw and away from the plane of the screws when released therefrom, ratchet

mechanism combined with said wrench for turning the same, and an operating handle for operating said wrench through said ratchet mechanism.
